UNITED STATES PATENT OFFICE.

HENRY W. PRATT, OF JERSEY CITY, NEW JERSEY, ASSIGNOR TO WILLIAM H. LUTTON COMPANY, A CORPORATION OF NEW JERSEY.

DESIGN FOR A PULLEY BRACKET.

Application filed April 3, 1929. Serial No. 30,742. Term of patent 14 years.

To all whom it may concern:

Be it known that I, HENRY W. PRATT, a citizen of the United States, and a resident of Jersey City, in the county of Hudson and State of New Jersey, have invented a new, original, and ornamental Design for Pulley Bracket, of which the following is a specification, reference being had to the accompanying drawing, forming part thereof.

Figure 1 is a side elevation of the pulley bracket showing my new design, and Figure 2 is a front elevation thereof.

I claim:

The ornamental design for a pulley bracket, as shown.

HENRY W. PRATT.
